UNITED STATES PATENT OFFICE

JOSEPH KALNITZ, OF CINCINNATI, OHIO

DESIGN FOR A VIOLIN

Application filed June 20, 1930. Serial No. 36,112. Term of patent 3½ years.

To all whom it may concern:

Be it known that I, JOSEPH KALNITZ, a citizen of the United States, residing at Cincinnati, in the county of Hamilton and State of Ohio, have invented a new, original, and ornamental Design for Violins, of which the following is a specification, reference being had to the accompanying drawing, forming part thereof.

Fig. 1 is a front view, and

Fig. 2 an edge view of a violin showing my new design, the essential features of which are represented by the full lines.

I claim:

The ornamental design for a violin, substantially as shown and described.

JOSEPH KALNITZ.
